CALEB ADDISON MCCOLLUM, DECEASED, LATE OF CLAIRTON, PENNSYLVANIA, BY FLORENCE WOODS MCCOLLUM, EXECUTRIX, OF PITTSBURGH, PENNSYLVANIA, AND JAMES MCINTOSH, OF PITTSBURGH, PENNSYLVANIA

BIN GATE

Application filed January 5, 1926. Serial No. 79,464.

This invention relates to mechanically operated gates for storage bin hoppers and the like, which deliver material into other receivers such as larry cars, trucks and the like, and while not limited thereto, relates more particularly to mechanically operated gates for the hoppers of coal storage bins used in connection with by-product coke ovens.

By-product coke ovens are charged with coal by a larry car carrying four or more measuring hoppers, which car travels along the top of a battery of ovens from the coal bin, where the coal drops into the oven through suitable charging holes which are closed by lids during the coking period. The coal bin, which holds the charging stock of coal, is so arranged that when the larry car carrying the measuring hoppers is in position for loading with coal, each hopper is under a coal bin discharge gate.

Heretofore, the coal bin discharge gates have been separately and manually operated. Owing to the very frequent opening and closing of the discharge gates which are quite large and heavy, and the heavy weight of the coal against which they must be operated, the operators are frequently injured due to the jerking and strain necessary to move the gates.

The present invention provides mechanical means for operating all of the gates of the coal bin simultaneously, thereby speeding up the filling of the larry car and eliminating the manual operation with its resultant injuries.

In the drawings:

Figure 1 is an end elevation showing the lower end of a coal storage bin, the larry car and the upper portion of a battery of coke ovens.

Figure 2 is an enlarged detail elevation showing the bin hopper gates and the gate operating mechanism carried on the larry car.

Figure 3 is a sectional elevation on the line III—III of Figure 2.

Figure 4 is a sectional elevation on the line IV—IV of Figure 2.

Figure 5 is a sectional elevation on the line V—V of Figure 2.

Referring more particularly to the draw-

ings, the letter A designates the battery of coke ovens, the letter B designates the coal storage bin as a whole, and the letter C designates the coal charging or larry car as a whole.

The bin B has its bottom constructed to form four hoppers 3, 4, 5 and 6 which are closed by discharge gates D.

The larry car C is adapted to travel along the top of the battery of ovens A on tracks 2 and has its body formed as four measuring hoppers 7, 8, 9 and 10. The car C is adapted to be positioned under the storage bin B so that the hoppers 7, 8, 9 and 10 of the car are alined with the lower ends of the hoppers 3, 4, 5 and 6, respectively, of the bin B to receive coal from the bin hoppers when the gates D are opened.

The hoppers 7, 8, 9 and 10 of the larry car C are provided with extension tubes or chutes 7^a, 8^a, 9^a and 10^a, respectively, adapted to receive the coal from the hoppers 3, 4, 5 and 6 of the bin.

The discharge gates D each comprise a body portion 11 to which is attached a moving cut-off plate 12 having brackets 15 to which are journaled flanged rollers 13 adapted to travel on track members 14 secured to the gate body 11. The rollers 13 are restrained from vertical movement by guide angles 16 secured to the gate body 11 by bolts 17. The tracks 14 and guide angles 16 are strengthened by being connected at their overhanging ends by a web plate 18. It will thus be understood that the cut-off plates or closures of the gates are supported in a fixed horizontal plane by the rollers 13 and are free to move backward and forward in this plane to open or closed position.

To simplify the operating mechanism and save time, it is desirable to simultaneously fill the four measuring hoppers 7, 8, 9 and 10 of the larry car C. Therefore, the cut-off plates or closures 12 are rigidly connected together by angles 19 which extend between the several cut-off plates and are secured thereto by bolts 19^a, forming a rigid unit of all the four plates or closures.

A trigger plate 20 is freely suspended between two transverse angle members 21 and

22 which are secured between the angle members 19 extending between the plates on the hoppers 4 and 5 of the bin B. The angle members 21 and 22 are spaced to form a slot 5 in which the trigger plate 20 is free to move in a vertical direction and said trigger is prevented from falling through the slot due to its upper end being bent at right angles to the main portion as at 20^a. The function 10 of the trigger 20 will be clearly set forth below.

The coal bin discharge gate bodies 11 are provided with a movable section 26 hinged to lugs 27 on the body and normally held 15 in closed or vertical position by the tension of spring 28 on rods 29. The movable section 26 and springs 28 are of sufficient size and strength to relieve any pressure that would prevent the total closing of the cut-off plate or closure 12 due to a lump of coal being caught between the edge of the advancing cut-off plate 12 and the movable section 26; but under normal conditions the springs 20 28 are sufficiently strong to hold the section 25 26 in closed or vertical position against the coal pressure in the bin when the closure 12 is advancing to closed position.

The larry car C is provided with an elevated frame work 38 adapted to support the 30 novel power operated gate operating unit designated as a whole by the letter E.

The unit E comprises a suitable reversing motor 31 which transmits power through a coupling 32 to speed reducing worm gear 35 33 thence through a coupling 34 and shaft 35 to a pinion 36. The pinion 36 is in mesh with a rack 44 on a ram 44^a which carries 40 two lugs 23 and 24 which are adapted to engage the trigger plate 20 when the larry car E is positioned for loading and the unit E is operated to open or close the cut-off or closure plates 12.

Pinion 36 revolves with the shaft 35 which shaft is journaled in bearings 40 in a housing 41 and moves the ram 44^a which is slidably mounted in guides 42 formed in the top of the housing 41. Ram 44^a is held in the guides 42 on the housing 41 by plates 43 bolted to the housing 41.

50 The lugs 23 and 24 are pivoted on pins 37 mounted at 37^a on the rack 44^a and are adapted to move through a 90 degree angle in such a manner that in case the ram 44^a is not in position with the trigger plate 20 55 between the lugs 23 and 24, ram 44 may be moved and the lug 23 or 24 as the case may be, will revolve about the pin 37 for permitting the lug to pass under the trigger plate 20 and the lug will then return by 63 gravity to normal position. The outer faces or backs of the lugs 23 and 24 are beveled so that in case the lug 23 or 24 as the case may be, did not revolve freely about the pin 37 the trigger plate 20, due to it being free 65 to move vertically, will travel upwardly along

the beveled face of the lug and over the top thereof and then drop between the lugs.

In order to prevent the overtravel of ram 44^a, a limit switch of any standard design, indicated at 45, is provided at each end of the unit E. The switches 45 are connected in the motor circuit and are adapted to break the motor circuit when the ram 44^a has reached the limit of its travel in the direction in which it is being moved, but 70 not interfering with the reverse motor circuit, so that the motor may be operated to reverse the travel of the ram. 75

As a safety feature, a limit switch 39, of standard design, is provided, and is connected in the circuit to the traction motor (not shown) of the larry car C and is adapted to open this circuit when the ram 44^a is moved to open the closure plates 12 and to remain open until the ram returns to the position to close the plates 12, thus preventing moving the larry car except when the closure plates 12 are closed. 80

In operation the larry car C is positioned under the coal bin B so that the chutes 7^a, 8^a, 9^a and 10^a of the hoppers 7, 8, 9 and 10, respectively, of the larry car, are in alignment with the discharge gates D of the bin hoppers 3, 4, 5 and 6. The operator of the larry car C will then make the circuit to the motor 31 through the means of a suitable controller or the like (not shown) and the pinion 36 will be operated to move the ram 44^a to the left causing lug 24 to engage the trigger plate 20 and move the closure plates 12 into open position. When the ram 44^a reaches its limit of travel the switch 45 will automatically break the motor circuit to stop the motor 31 if the operator has not already broken the circuit by the controller. When the hoppers 7, 8, 9 and 10 of the larry car C have received the required amount of coal, the operator will 100 operate his controller to make a reverse motor circuit to the motor 31, thereby causing the pinion 36 to rotate in the reverse direction and move the ram 44^a to the right, causing lug 23 to engage the trigger plate 20 and thereby move the closure plates 12 into 105 closed or cut-off position. When the ram 44^a reaches its limit of travel the switch 45 will automatically break the motor circuit to the motor 31 if the operator does not break the circuit by his controller. 110

115 The lugs 23 and 24 are pivoted on pins 37 mounted at 37^a on the rack 44^a and are adapted to move through a 90 degree angle in such a manner that in case the ram 44^a is not in position with the trigger plate 20 55 between the lugs 23 and 24, ram 44 may be moved and the lug 23 or 24 as the case may be, will revolve about the pin 37 for permitting the lug to pass under the trigger plate 20 and the lug will then return by 63 gravity to normal position. The outer faces or backs of the lugs 23 and 24 are beveled so that in case the lug 23 or 24 as the case may be, did not revolve freely about the pin 37 the trigger plate 20, due to it being free 65 to move vertically, will travel upwardly along

120 As soon as the ram 44^a starts to move to the left to open the closure plates 12 the automatic switch 39 will break the circuit to the larry car traction motor (not shown) and said circuit will remain broken until the ram 44^a has returned to the right-hand position to close the closure plates 12. 125

130 While we have shown and described one specific embodiment of our invention, it will be understood that we do not wish to be limited thereto since various modifications

may be made without departing from the scope of our invention as defined in the appended claims.

We claim:

5. 1. The combination with a material delivering hopper, of a gate for closing the lower delivery end of said hopper, and a vehicle for receiving the material delivered from said hopper, said gate comprising a body portion, a horizontally reciprocating gate member, a movable side member on said body adapted to move outwardly if any material is caught between the end of said reciprocating gate member and gate body when 70
10 said gate member is being closed, and a power operated unit carried by said vehicle for opening and closing said gate member. 75
15 2. The combination with a plurality of material delivering hoppers having movable gates for closing their delivery ends, of means for connecting all of said gates together, a power operated vehicle for receiving material from said hoppers, a power operated unit carried by said vehicle for opening and closing said gates, and means for rendering said power operated vehicle inoperative when said power operated unit is in operation. 80
20 3. The combination with a plurality of material delivering hoppers having movable gates for closing their delivery ends, of means for connecting all of said gates together, a power operated vehicle for receiving material from said hoppers, a power operated unit carried by said vehicle for opening and closing said gates, means forming an operative connection between said power operated unit and said gates, said means being inoperative until said vehicle is positioned to 85
25 receive the material delivered from said hoppers, and other means for rendering said power operated vehicle inoperative while said power operated unit is in operation. 90
30 4. The combination with a plurality of material delivering hoppers, of gates for closing the delivery ends of said hoppers, and an electrically propelled vehicle for receiving the material delivered from said hoppers, said gates each comprising a body portion, track members on said body portion, a wheeled horizontally reciprocable closure member for closing the lower end of said body portion mounted on said track members, means for rigidly connecting all of said closure members together, an electrically operated unit carried by said vehicle for opening and closing said gates, and mechanical means carried by said gates forming an operative connection between said electrically operated unit and said gates, said means being inoperative until said vehicle is positioned to receive the material delivered from said hoppers. 95
35 5. The combination with a plurality of material delivering hoppers, of gates for closing the delivery ends of said hoppers, and an electrically propelled vehicle for receiving the material delivered from said hoppers, said gates each comprising a body portion, track members on said body portion, a wheeled horizontally reciprocable closure member for closing the lower end of said body portion mounted on said track members, means for rigidly connecting all of said closure members together, an electrically operated unit carried by said vehicle for opening and closing said gates, and means for breaking the electric circuit to said electrically operated vehicle to render said vehicle inoperative when said electrically operated unit is being operated. 100
40 6. The combination with a plurality of material delivering hoppers, of gates for closing the delivery ends of said hoppers, and an electrically propelled vehicle for receiving the material delivered from said hoppers, said gates each comprising a body portion, track members on said body portion, a wheeled horizontally reciprocable closure member for closing the lower end of said body portion mounted on said track members, means for rigidly connecting all of said closure members together, an electrically operated unit carried by said vehicle for opening and closing said gates, means for limiting the opening and closing movement of said unit, and means for automatically rendering said vehicle inoperative when said unit is being operated. 105
